SECRET SIGNALING SYSTEM

Carl Edward Atkins, Evanston, Ill., assignor to
 Tung-Sol Lamp Works, Inc., Newark, N. J., a
 corporation of Delaware

Application October 2, 1943, Serial No. 504,679

9 Claims. (Cl. 178—22)

1

My present invention relates to secret station-to-station signaling systems of the general type disclosed and claimed in my copending application Serial No. 443,898, filed May 21, 1942, and comprises an improved and simplified system of that type particularly adapted for secret telegraphic communication.

In my present system, as in that of my above mentioned application, secrecy is obtained by scrambling the signal introduced at one station with the signal introduced at the other station and detection of the communicated signal is obtained by cancellation from the incoming energy of the modulation corresponding to the signal previously introduced at the same station.

For an understanding of the improved system of the present invention reference may be had to the specific and preferred embodiment of the invention employing frequency modulation illustrated in the drawing, of which—

Fig. 1 is a diagrammatic circuit drawing of the apparatus at either of two communicating stations equipped with a secret signaling system embodying the invention;

Fig. 2 is a diagram of the special network of Fig. 1 at one station; and

Fig. 3 is a diagram of the special network of Fig. 1 at the other station.

As shown in Fig. 1, the equipment at each station in the specific embodiment of the invention illustrated includes a receiving antenna 1, a wave trap 2 tuned to the frequency of the local transmitter, a receiver 3 tuned to the frequency transmitted at the cooperating station, a limiter 4, an amplifier 5 and a frequency detector 6 the output circuit of which includes a phase shifting network comprising a capacity 7 and adjustable resistance 8 connected in series and capacity 9 connected in shunt across a resistance 10. A resistance 11, grounded at one end, is connected at its other end to a tap on resistance 10 and to the control grid of a triode 12. The cathode of tube 12 is suitably biased by a network 13 as is also the cathode of a triode 14 connected in tandem with tube 12. The pair of tubes 12 and 14 operate, as herein-after more fully described, to cancel the frequency deviations corresponding to the signal previously introduced at the local station and hence may be termed a "cancellation mixer." The plates of tubes 12 and 14 are parallel connected and the output from this pair of tubes, which appears across a tuned circuit 15, connected to a source of power through a filter 16, is fed through a blocking condenser 17 to a pair of parallel connected resistors 18 and 19. A tap on resistor 18

2

connects to any suitable audio frequency amplifier and reproducer (not shown) such as a loud speaker or the like, while a tap on resistor 19 is connected to the control grid of a triode 20 connected in tandem with a triode 21. The cathodes of tubes 20 and 21 are biased by the network 13 and the plates of this pair of tubes are connected in parallel to a tuned circuit 22 which is connected with the power source through the filter 16. As hereinafter described, tube 21 operates to add the local signal to that introduced at the cooperating station and hence this pair of tubes may be termed the "injection mixer." The output of the pair of tubes 20 and 21, appearing across the tank circuit 22 is fed through a blocking condenser 23 to a reactance tube 24 which controls the frequency of an oscillator 25. The output from oscillator 25 energizes a power amplifier 26 and transmitting antenna 27.

20 For the introduction of the signal each station includes an oscillator 28 operating at a low frequency of say 100 cycles per second, a key 29 and a special network 30 which includes phase shifting means and which delivers a portion of the 25 signal energy through a delay network 31 to the control grid of tube 14 and another portion of the signal energy to the control grid of tube 21.

Network 31 may be any known type of delay network, as for example a resistor-condenser 30 combination or an inductor-condenser combination, and network 30 may be any network which includes suitable phase shifting means and preferably also at least one of the stations amplitude control means. Before describing specific circuits 35 suitable for use as the network 30, which circuits are shown in Figs. 2 and 3, the operation of the system as a whole will be described. For convenience in understanding the operation, the units at one station, say station A, will be identified by 40 the subscript *a* and the units at the other station, say station B, will be identified by the subscript *b*. At station A when key 29a is operated, a part of the energy is supplied through network 30a to the grid of tube 21a, whereupon the output from tube 45 21a appearing across tank 22a modulates the reactance tube 24a and a frequency modulated signal is transmitted from antenna 27a. At station B the transmitted energy is received and amplified and then demodulated in detector 6b. The 50 phase of the signal energy is shifted by the network 7b—8b—9b and a suitable portion thereof applied from resistor 10b to the grid of tube 12b. An amplified signal appears across tank 15b and is applied through blocking condenser 17b and control 19b to the grid of tube 20b. Appearing in

the output across tank circuit 22b the signal energy serves to modulate reactance tube 24b. This frequency modulated signal after a brief interval is received at station A where it originated and upon demodulation in detector 6a has its phase shifted in network 7a—8a—9a. A portion thereof is then applied to the control grid of the tube 12a. In the meanwhile energy resulting from the operation of key 29a and delivered through network 30a to delay network 31a has been delayed in the latter network and is applied to the control grid of tube 14a simultaneously with the arrival of the returning signal to the grid of tube 12a and in phase opposition thereto. Consequently there will be no corresponding output across tank 15a. If, however, key 29b has been depressed during this interval, the phase angle of the incoming signal will be such as to yield an output across 15a which can be heard as an audio signal at station A and which is also applied to the grid of tube 20a for addition across tank 22a to the continuing signal delivered to tube 21a from network 30a. The operation at station B, including the cancellation of the locally introduced signal by tubes 12b and 14b and the addition of the signal by tubes 20b and 21b is of course the same as above described for station A.

In the system of Fig. 1 the network 30a and 30b may be identical but I prefer, however, in order to provide a flexible system with a wide range of adjustment of the phase shift and of the amplification, to employ for one network 30 the circuit shown in Fig. 2, and for the other network 30 the circuit shown in Fig. 3. As shown in Fig. 2, one network 30 includes a master resistor 32 grounded at one end and connected at its other end to the key 29 and a pair of subsidiary resistors 33 and 34 connected in parallel to an adjustable tap on resistor 32. A tap on resistor 33 supplies energy to the primary of a transformer 35 the secondary of which energizes the grid of tube 14 through a polarity reversing switch 36 and delay network 31. A tap on resistor 34 connects through a phasing network 37 to the grid of tube 21.

Unit 30 of the other station, as shown in Fig. 3, includes a master resistor 38, a tap on which is connected through a phase shifting network including a resistor 39, condenser 40 and resistor 41, to the grid of a triode 42. Triode 42, which is suitably biased by a network 43, amplifies the signal energy and changes its phase by 180°. The output circuit of triode 42 includes the primary of a transformer 44 the secondary of which is connected to parallel connected resistors 45 and 46. A tap on resistor 45 is connected to the grid of tube 14 through delay filter 31 and a tap on resistor 46 is connected to the control grid of tube 21.

For efficient operation of the above described system the oscillators 28a and 28b should be synchronized and their outputs maintained in phase. Known stabilizing means could be provided at each station for this purpose or the frequency of one oscillator could be locked to that of the other by the transmission from one station to the other of a modulating tone as disclosed in a copending application of mine, Serial No. 501,529, filed September 8, 1943. The networks 7—8—9, 39—40—41, 37 and 31, together with the polarity reversing switch 36, provide ample means for adjusting the phase of the signal energy at any point in the system, the amplifier 5 and triode 42 provide amplification,

5 and the master resistors 32 and 38 together with the numerous other tapped resistors provide means for adjusting the volume of the signal energy and the proportionate distribution thereof. Preferably the various phase shifting networks and amplitude control means of the system are so adjusted that the signal energy delivered to the control grid of tube 21 will be of equal amplitude and 120° out of phase with that delivered to the control grid of tube 20. As disclosed in my said copending application Serial No. 501,529, filed September 8, 1943, phase difference of this amount in the signal energies to be mixed when the amplitudes are equal enhance the secrecy of 10 the system as it insures that there will be no change in amplitude in the radiated signal irrespective of whether one or both keys 29 are depressed.

15 From the foregoing description it will be apparent that the present invention provides an efficient secret station-to-station signaling system wherein the signal originating at one station is scrambled with the signal introduced at the other station whereby simultaneous introduction of keyed intelligence at the two stations produces a conglomerate of characters on a more or less capricious basis, resulting in a signal unintelligible to an eavesdropper. While the preferred form of the invention utilizes frequency modulation as a means for carrying the signal energy to and from the communicating stations, amplitude modulation or phase modulation can likewise be employed.

20 The following is claimed:

35 1. A secret station-to-station signaling system comprising in combination equipment at each station including receiving means, detecting means connected to receive energy from said receiving means, a pair of electron tubes connected in tandem, a phase-shift network between said detecting means and the control grid of one of said tubes, signal introducing means, means for creating a delayed replica with shifted phase of the signal introduced by said introducing means and for applying the same to the control grid of the other one of said pair of tubes, a second pair of tubes connected in tandem, a tuned output circuit for said first pair of tubes connected to the control grid of one of said second pair of tubes, means for impressing signal energy from said signal introducing means to the control grid of the other one of said second pair of tubes, transmitting means and means for modulating the energy transmitted by said transmitting means by the output from said second pair of tubes whereby said first pair of tubes may be operated as a cancellation mixer to cancel from the incoming energy at one station energy corresponding to the signal previously introduced into the system at the same station and said second pair of tubes may be used to scramble the outgoing signal with the signal introduced at the other station.

40 2. In a secret station-to-station signaling system of the type wherein signal energy introduced at one station and transmitted therefrom to the other station is mixed at the latter station with signal energy introduced at the latter station, the improvement which comprises at each station a pair of electron tubes connected in tandem, means for impressing upon the grid of one of said tubes demodulated energy received from the other station, means for impressing upon the grid of the other of said tubes a delayed replica of the signal energy introduced at the same station for cancel-

ing in the output of said tubes that portion of the demodulated energy received from the other station but previously originating at the same station, a second pair of electron tubes connected in tandem, means for energizing the grid of one of said second pair of tubes from the output of said first pair of tubes, means for energizing the grid of the other of said second pair of tubes with signal energy introduced at the same station, and means connected to the output circuit of said last pair of tubes for modulating the energy transmitted from the station.

3. The method of operating a secret station-to-station communication system which comprises at each station dividing the signal energy into two portions, delaying one portion and shifting the phase thereof, scrambling the other portion with signal energy introduced at the other station, utilizing the scrambled portion to frequency-modulate the energy transmitted from the station, and utilizing the delayed phase shifted portion for separating the signal energy introduced at the other station from the energy received and detected at the same station.

4. The method of operating a secret station-to-station communication system which comprises at each station dividing the signal energy into two portions, delaying one portion and shifting the phase thereof, scrambling the other portion with signal energy introduced at the other station, utilizing the scrambled portion to modulate the energy transmitted from the station, utilizing the delayed phase shifted portion for separating the signal energy introduced at the other station from the energy received and detected at the same station, maintaining the signal energies introduced at the two stations equal in amplitude and adjusting the relative phase of the signal energies to be 120° out of phase when scrambled.

5. In a secret station-to-station signaling system of the type described, the improvement which comprises at each station a cancellation mixer and an injection mixer, said cancellation mixer including a pair of electron tubes connected in tandem, means for applying to the control grid of one of said tubes energy having components corresponding to the signal previously introduced at the same station and the signal introduced at the other station, means for applying to the control grid of the other tube energy corresponding to the signal previously introduced at the same station but 180° out of phase with the corresponding component of energy applied to the control grid of the first mentioned tube and said injection

mixer comprising a second pair of electron tubes connected in tandem, means for energizing the control grid of one of said last mentioned pair of tubes with the output of the cancellation mixer and means for energizing the control grid of the other one of said last mentioned pair of tubes with signal energy introduced at the same station.

6. In a secret signaling system of the type described, the combination at each station of a low frequency source of signal energy, a key, a network receiving energy from said source under control of said key, said network including phase shifting means and means for dividing the energy received from the source into two portions, means for scrambling one of said portions with energy received from the other station and corresponding to a portion of the energy of the source at the other station, transmitting means, means for modulating the energy transmitted by said transmitting means with said scrambled portions, means for delaying said other portion, receiving and detecting means, and means for utilizing said delayed portion for unscrambling the detected energy received from the other station.

7. The combination according to claim 6 wherein said network at one station includes a resistor, grounded at one end and connected to said key at its other end, a pair of resistors connected in parallel to a tap on said first mentioned resistor and a pair of phase shifting circuits each connected to a tap on one of said last mentioned resistors, whereby one portion of the signal energy is delivered through one of said phase shifting circuits and the other portion through the other of said phase shifting circuits.

8. The combination according to claim 6 wherein in the network at one of said stations comprises a resistor grounded at one end and connected to said key at its other end, a phase shifting circuit connected to a tap on said resistor, a triode energized from said phase shifting circuit, and a pair of parallel connected resistors in the output of said triode whereby said portions of signal energy may be tapped from said last mentioned resistors.

9. The combination according to claim 6 wherein in the phase shifting means of said network at one station are arranged to shift the phase of one of the portions of energy relative to that of the other portion of energy and the phase shifting means of the network of the other station are arranged to shift the phase of the signal energy prior to division into portions.

CARL EDWARD ATKINS.
